(57) **CLAIM**

The ornamental design for a shoe as shown and described.

DESCRIPTION

FIG. 1 is a perspective view of a first embodiment of a shoe showing my new design;

FIG. 2 is another perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof;

FIG. 8 is a rear elevational view thereof;

FIG. 9 is an enlarged view of portion 9 shown in FIG. 2;

FIG. 10 is a perspective view of a second embodiment of a shoe showing my new design;

FIG. 11 is another perspective view thereof;

FIG. 12 is a top plan view thereof;

FIG. 13 is a bottom plan view thereof;

FIG. 14 is a left side elevational view thereof;

FIG. 15 is a right side elevational view thereof;

FIG. 16 is a front elevational view thereof;

FIG. 17 is a rear elevational view thereof; and,

FIG. 18 is an enlarged view of portion 18 shown in FIG. 11. The dash-dash broken lines in the drawings depict portions of the a shoe that form no part of the claimed design.

The dot-dash broken lines represent boundaries of the enlarged portions and form no part of the claimed design.

1 Claim, 18 Drawing Sheets
